UNITED STATES PATENT OFFICE.

JOHANNES KARL RUTHS, OF DJURSHOLM, SWEDEN, ASSIGNEE TO AKTIEBOLAGET
VAPORACKUMULATOR, OF STOCKHOLM, SWEDEN, A CORPORATION.

STEAM-ACCUMULATOR APPARATUS FOR STEAM PLANTS.

Application filed November 1, 1919. Serial No. 335,113.

To all whom it may concern:

Be it known that I, JOHANNES KARL RUTHS, subject of the King of Sweden, residing at Djursholm, in the Kingdom of Sweden, have invented certain new and useful Improvements in Steam-Accumulator Apparatus for Steam Plants, of which the following is a specification.

In steam plants provided with steam accumulators, a valve mechanism has been arranged in a conduit supplying steam from the generator to the accumulator and it operated, when the pressure in the conduit increased above a predetermined value to 10 increase the steam supply through the conduit, and it acted to throttle the steam supply upon a decrease of the pressure below a predetermined value, the object of such an arrangement being to maintain a practically constant pressure in the steam generator and in the connected conduit system in order to bring about an independence between the momentary steam generation and steam consumption. In the operation of such plants however the drop in pressure due to the throttling down of the steam took place at the valve mechanism itself and no power was extracted in this pressure drop. By causing this drop of pressure to take 20 place within a steam motor certain advantages are gained, and power may be extracted from the steam before it is lead to the accumulator. In a copending application filed by me of even date herewith, Serial No. 335,112, I have described and claimed a steam accumulator plant wherein it is possible to obtain power from the steam available, even on great variations in the steam consumption, or steam supply, or both, and wherein the pressure in the boiler is maintained at a constant value, so that the boilers may operate at the highest efficiency, and this was effected by arranging a steam motor to receive steam from the generator 30 and to supply steam to the accumulator, and a valve mechanism to control the flow of steam to the motor and governed in its action by the pressure of steam in front of the valve mechanism.

The present invention aims to effect this same general result, and the invention consists of an improved arrangement of parts, which will be fully described hereinafter in detail, whereby the invention is more particularly adaptable in its application to the

type of steam motors now universally employed.

In my present invention, a steam motor is employed comprising a plurality of units including a high pressure unit and a low pressure unit, the high pressure unit being supplied with steam from a conduit connected with the generator, and the low pressure unit receiving steam from the high pressure unit directly or through an intermediate pressure unit, a steam accumulator being supplied with steam from the motor, and a valve mechanism being inserted in the connection leading steam to the low pressure unit and actuated by the pressure in the conduit from which the high pressure unit is supplied in order to control the steam supplied to the low pressure unit, and a regulating means is provided to control the steam supplied to the high pressure unit. The form of these parts is such that if the pressure in the conduit from which the high pressure unit is supplied, should increase, the valve mechanism will throttle the steam supply to the low pressure unit, whereby the said regulating means will act to admit more steam from said conduit to the high pressure unit, and more steam will flow to the accumulator; and if on the other hand the pressure in the said conduit decreases, the steam supply to the low pressure unit will be increased, thereby causing the regulating means to decrease the steam supply from the conduit to the high pressure unit.

Thus when the pressure in the conduit from which the high pressure unit is supplied increases due to a momentary surplus of steam generated over the momentary consumption, this surplus of steam generated is led through the high pressure unit to the accumulator and at the same time, to facilitate this object, the load on the low pressure unit is, in part or in whole, transferred to the other unit or units.

The invention consists also in the details of construction and combination of parts hereinafter described and claimed.

The invention will be described more in detail in reference to the examples shown in the accompanying drawings, in which:

Fig. 1 is a view of a steam plant having my invention embodied therein with a steam motor of the single extraction type.

Fig. 2 is a view of a plant similar to that shown in Fig. 1, but with a different

relative arrangement of the steam consumers.

Fig. 3 is a view similar to Fig. 2, but with a steam motor of the double extraction type.

Fig. 4 is a sectional view of the valve mechanism for controlling the steam supply to the low pressure unit of the motor.

Fig. 5 is a sectional view of two mechanically interconnected valves controlled by the pressure in the conduit supplying the motor.

Fig. 6 is a sectional view of two mechanically interconnected valves controlled by a single speed governor.

Referring to the drawings:

Referring to Fig. 1 a steam motor, in this case a turbine is shown comprising a high pressure unit H and a low pressure unit L . The high pressure unit receives steam from a steam generator P through a conduit L_1 and a branch conduit L_t , and steam is supplied to the low pressure unit from the high pressure unit by means of a conduit L_b connecting the two units, in which conduit there is inserted, in accordance with my invention, a valve mechanism V_1 . This valve mechanism is operated by the pressure in the conduit L_1 acting through a conduit L_v , the valve mechanism being of a form and construction, as will be more fully described later on, which will increase the supply of steam to the low pressure unit upon a decrease of the pressure in the conduit L_1 below a predetermined value, and which will throttle the steam supply to the low pressure unit upon an increase of pressure in the said conduit above a predetermined value.

A steam accumulator A is arranged to receive steam from the motor, in the present instance through a conduit L_h leading from the conduit L_b at a point in front of the valve V_1 , and connecting with a conduit L_a to which the accumulator is connected in parallel, suitable non-return valves $B-B$ being inserted in the connections between the accumulator and the conduit L_a ; and the direction of steam flow through the non-return valves being indicated by the arrows.

The supply of steam to the high pressure unit through the conduit L_t is controlled by regulating means, in the present instance in the form of a valve mechanism V operated by a centrifugal governor C driven from the turbine, the form of the valve and its connection with the governor C as shown, being such that if the speed of rotation of the turbine increases above normal, the valve will throttle the steam supply to the high pressure unit; and if the speed of the motor falls below normal, the valve will be moved and the supply of steam will be increased.

A valve V_2 is inserted in the conduit L_b ,

in the present instance between valve V_1 and the low pressure unit, and this valve is operated by a centrifugal governor C_2 , the form of the valve and its connection with the governor being such as shown, that at the normal speed of rotation of the turbine, the valve V_2 will be held fully open with the governor balls in the position shown, and will only come into operation to close valve V_2 at a speed higher than that at which governor C closes valve V_1 . Thus it will be seen that the governor C_2 operates only in exceptional cases when governor C has closed valve V_1 , and the speed of the motor is even then too high due to supply of steam from the accumulator through line L_h to the low pressure unit.

A condenser Y is connected to the low pressure unit; and the turbine is shown as driving an electric generator G .

To the conduit L_a , a conduit L_s is connected by means of a reducing valve R_{a_3} adapted to control the steam supply to the conduit L_s to maintain a practically constant pressure therein; and the steam consumer, for example a paper making machine M , is connected to the said conduit.

Conduit L_a is connected with conduit L_1 by means of a connecting conduit L_{ax} , and a valve mechanism O_{1a} , which I term an "overflow valve", is inserted therein, the function of which is to admit steam from the conduit L_1 to the accumulator, only when in exceptional cases, the pressure of steam in conduit L_1 exceeds a predetermined value, at which pressure, valve V_1 will be completely closed. The two valves O_{1a} and V_1 may be mechanically interconnected as shown for example in Fig. 5, in order that they will operate in the proper relations to each other, as will be presently described.

A reducing valve R_{1a} is arranged in the system in parallel with the said valve O_{1a} , to admit steam to the conduit L_a in case the accumulator should become fully discharged which may infrequently occur.

A steam consumer S , which may be in the form of a paper pulp digester, is shown as connected with the conduit L_1 , but such consumer may be omitted, as it is not essential to the operation of the plant in realizing all of the advantages of the present invention.

In the operation of the plant with the parts arranged as described, wherein a steam motor is arranged in the system between the generator and the steam accumulator, and wherein the accumulator receives steam under normal conditions of operation, from the motor, the accumulator will take care of all variations in the plant. Assuming for instance, that the pressure in conduit L_1 increases above a predetermined value, due to decreasing steam consumption in the consumer S , or to increase of steam generation

in the generator P, the valve V_1 will throttle the steam supply to the low pressure unit of the motor and consequently the rate of speed of the motor will fall below normal, 5 and the governor C will act on the valve V and increase the steam supply to the high pressure unit. It is therefore seen that at an increase of pressure in conduit L_1 , the surplus steam will be led through the high pressure 10 unit to conduit L_a by which power will be obtained from the steam, while the low pressure unit will be unloaded in a corresponding degree. From the conduit L_a , the steam can flow either to conduit L_s through 15 the reducing valve R_{as} , or to the accumulator A, or to both, depending upon the pressure conditions.

If on the other hand the pressure in conduit L_1 should decrease below a predetermined value, due to increased steam consumption, or to decreased steam generation, 20 valve V_1 will be operated to increase the steam supply to the low pressure unit, and consequently the speed of rotation of the 25 motor will be increased above normal, and the governor C will act on valve V and will decrease the steam supply to the high pressure unit. If in these circumstances, insufficient steam is being supplied from the high 30 pressure unit to the low pressure unit, the deficiency can be met by steam from the accumulator, which deficiency under the conditions described, will be supplied from the accumulator through conduits L_a , L_b and L_s , 35 whence it will pass to the low pressure unit.

Assuming now that the demand for power is increased beyond that being furnished by the steam motor, then the speed of the rotation of the motor will fall, and the governor 40 C will act to admit more steam to the high pressure unit. As a result, the pressure in conduit L_1 will decrease and consequently valve V_1 will be actuated to admit more steam to the low pressure unit, which steam 45 may be taken from the high pressure unit only, or partly from which the high pressure unit and partly from the accumulator according to the conditions. The speed of rotation of the motor will therefore increase, 50 and the governor C will act to throttle the steam supply to the high pressure unit. If, in these circumstances, insufficient steam is being supplied from the high pressure unit to the low pressure unit, the deficiency, as in 55 the previous case where it was assumed that pressure in conduit L_1 decreased, can be met by steam from the accumulator, so that where energy demand is greater than what is supplied from conduit L_1 to the motor as a 60 whole, the accumulator supplies the deficiency.

From the foregoing description it will be understood that the steam supplied by the accumulator to the low pressure unit had, 65 previous to its passage to the low pressure

unit, passed through the high pressure unit on its way to the accumulator, and power had therefore been obtained therefrom.

Again it will be understood that if the demand for power should decrease, the speed 70 of rotation of the motor will increase above the normal, and the steam supply to the high pressure unit will be throttled, and pressure in conduit L_1 increasing valve V_1 will be operated to decrease the steam supply 75 to the low pressure unit. Consequently the speed of rotation will decrease, and more steam will be led to the high pressure unit and thence to the accumulator. In this action therefore the low pressure unit will be 80 unloaded corresponding to the degree of decreased demand for power.

If the speed of rotation should increase to such a degree that the steam supply to the high pressure unit is fully shut off, then on 85 further increase of speed of the motor, governor C₂ will come into action and will operate valve V_2 and will throttle the steam supply to the low pressure unit coming from the accumulator.

By these different cooperative actions of the several parts, it will be seen that the pressure in conduit L_1 will be maintained at a practically constant value, notwithstanding 90 the varying conditions that may take place.

The devices shown in Fig. 1 take care of all variations in the system, which variations may be caused by an increase or a decrease in the steam consumption, or by irregularities in the fuel supply. These latter variations are, for instance, caused by slagging, or they may arise in the feeding of the boiler. In fact, measurements taken at a plant running under entirely normal conditions have shown that very great variations 100 may occur. But even in cases where the fuel is available in variable quantities, as, for instance, in the case of blast furnace gases, waste heat from furnaces, or other 110 sources of variable heat supply, the devices serve to maintain the boiler pressure at a fully constant value. The variations may occur in the power consumption of generator G. The same result will be obtained if the 115 consumption of consumers S and M, or both, equal zero.

Fig. 4 shows a form of the valve V_1 by way of example, suitable for the realization of my invention. Here it will be seen that 120 a valve casing 2 is formed with oppositely disposed ports 3 and 4 adapted to be connected in the conduit L_b , the port 3 being connected with a chamber 5 extending into the casing and having aligned ports 6 and 7. 125 These ports 6 and 7 are controlled by a balanced valve member 8 movable with a valve stem 9 guided in the casing, and having connected with it a piston F sliding in a cylinder 10. The piston is acted on at one side 130

by a spring 11 arranged within the cylinder, and on the other side by the pressure of steam in conduit L_1 acting through the conduit L_v which is connected to the end of the cylinder. The arrangement is such that the pressure of steam in the cylinder tends to hold the valve closed and the spring tends to open the valve. Therefore on the increase of steam pressure to a degree to overcome the spring, the valve will be closed and will throttle the steam supply through conduit L_b , and on the decrease of the pressure in the cylinder to a degree below the force of the spring, the latter will move the piston 15 and will open the valve and permit a freer passage of the steam.

Fig. 2 shows a steam plant of substantially the same construction as that shown in Fig. 1. In Fig. 2 however the steam from the motor is led to a conduit L_2 supplying a consumer B_2 , the said conduit L_2 connecting with conduit L_a by means of an over-flow valve O_{2a} , and the conduit L_a being connected with the accumulator as before. Also in this case the additional conduit L_2 is connected to the conduit L_1 by means of a reducing valve R_{12} , the over-flow valve O_{12} of Fig. 2 corresponding to the over-flow valve O_{1a} of Fig. 1. The operation of the parts as shown in this figure is, so far as the principle of my invention is concerned, substantially the same as the operation of the parts of Fig. 1.

Fig. 3 shows a plant substantially similar to that shown in Fig. 2, the main difference being that in Fig. 3 the turbine is of the double extraction type, comprising a high pressure unit H , an intermediate pressure unit M_e , and a low pressure unit L , the controlling valve V_1 being inserted in the connection between the intermediate pressure unit and the low pressure unit, the conduit L_a receiving steam from the intermediate pressure unit, and the conduit L_2 receiving steam from the high pressure unit. These two conduits are connected together by means of a branch conduit containing an over-flow valve O_{2a} , and a second branch conduit connects said conduits and contains a reducing valve R_{2a} , the said conduits L_a and L_2 supplying steam respectively to consumers M and B_2 . In the connection between the high pressure unit and the intermediate pressure unit, an overflow valve O_{2m} and a speed regulated valve V_3 are inserted. In this Fig. 3 speed governors C , C_1 and C_2 are provided in connection with the respective pressure units, which governors operate in the same relations to each other as the two governors of Fig. 2. The general operation of the plant in so far as the principle of my invention is concerned, is substantially the same as that described in connection with Fig. 1.

Fig. 5 shows the details of the mechanical

interconnection of the over-flow valve O_{1a} and the valve V_1 as hereinbefore referred to. Here it will be seen that a valve member 12 corresponding to valve O_{1a} of Fig. 1, and O_{12} of Figs. 2 and 3, and a valve member 13 corresponding to valve V_1 of Figs. 1, 2, 3, are arranged respectively in valve casings 14 and 15 contained in a single compact casing structure. The valve casing 14 is formed with two ports 16 and 17, the port 16 adapted to receive steam from conduit L_1 , and the port 17 adapted to supply steam to conduit L_a . A chamber 18 extends into the casing 14 from port 17 and is provided with aligned ports 19 and 20 which are controlled by the valve member 12. Casing 15 is formed with two ports 21 and 22, the port 21 receiving steam from the high pressure unit of the motor, and the port 22 supplying steam to the low pressure unit. Port 22 has connected with it a chamber 23 extending into the casing and provided with ports 24 and 25 controlled by the valve member 13. The two valve members 12 and 13 are mounted 90 loosely on a common valve actuating stem 26 guided in the casing structure and connected at one end to a piston 27 sliding in a cylinder 28, the said cylinder at one side of the piston being in communication 95 with the interior of the valve casing 14, and the piston on its opposite side being acted on by a spring 29 exerting its force in opposition to the pressure of the steam. Valve member 12 is engaged by a collar 30 100 on the stem and is acted on by a spring 31 surrounding the stem and tending to hold the valve member in closed position. Valve member 13 is engaged by a collar 32 on the stem and is acted on by a spring 105 33 sustained by the stem and tending to hold the valve member closed.

In the operation of this mechanism, if the pressure in conduit L_1 acting in casing 14, should fall below a predetermined value, 110 spring 29 will move the piston and connected valve stem, and collar 32 thereon engaging the valve member 13 will open the same and steam from the high pressure unit will flow to the low pressure unit 115 through ports 21 and 22. In this position of the parts, valve member 12 corresponding to the over-flow valve O_{1a} of Fig. 1, for instance, will remain closed, due to the action of its spring 31. If now pressure in conduit L_1 acting in valve casing 14 should increase, piston 27 will be moved in the opposite direction and will move valve stem 26, and valve member 13 will act to throttle the steam supply to the low pressure unit, 125 and when valve member 13 becomes completely closed due to further increase of pressure, valve member 12 will be opened by means of collar 30.

It is seen therefore that when valve mem- 130

ber 13 is closed and shuts off steam to the low pressure unit, a further increase of the pressure in conduit L_1 will open valve member 12 and steam will be led from conduit L_1 to the accumulator.

While in each of Figs. 1, 2 and 3 a plurality of speed governors is shown for the turbine, with each governor connected to operate its associated valve member, it will be understood that a single speed governor may be employed and connected to actuate a plurality of valve mechanisms, so that the valves will be operated in succession as the speed of the motor increases. Such a mechanism is shown in Fig. 6 with one speed governor operating two valve mechanisms. In this figure it will be seen that the two valve mechanisms V_2 and V have their valve stems S_3 and S_4 connected respectively with piston plungers 21 and 20 sliding in power cylinders, to which cylinders pressure fluid is admitted by pipes 25 and 24, and from which the pressure fluid exhausts by pipes 28 and 29, and pipes 26 and 27, the control of the pressure fluid to and from the cylinders being effected by slide valves 23 and 22 connected to levers 17 and 16, which levers are in turn connected to the valve stems S_3 and S_4 . The lever 17 is acted on by springs 19 which hold it yieldingly in a neutral position, and the end of the lever is formed with an opening through which loosely slides a rod 15 provided with spaced collars 18 disposed on opposite sides of the lever 17, this arrangement permitting of a limited movement or play of the rod relative to the lever without affecting the latter. The rod is connected to the lever 16 and to a lever 14 fulcrumed at one end, and a centrifugal governor $C-C_2$ is operatively connected with lever 14 to rock the same more or less according to the speed of revolution.

The relation and form of the above described parts are such that under the normal number of revolutions of the governor both valves will be held in open position as shown. Should the number of revolutions increase, valve V will start to close, in which action rod 15 will move, due to its play relative to the lever 17, without moving the latter, and consequently valve V_2 will remain open. If now the number of revolutions further increases, valve V will be completely closed, and in this action collar 18 will act on lever 17, and by means of slide 23 controlling the piston 21, valve V_2 will be throttled. The two valves V_2 and V correspond in this example to the valves V_2 and V of Fig. 1.

From the operation of the parts just described, it will be seen that at the normal speed of the motor, the steam supply to the high pressure unit will be controlled by valve V , while on further increase of speed

above normal, and resulting in the complete closure of valve V , valve V_2 controlling the steam supply to the low pressure unit, will begin to close and will thus throttle the steam supply to this unit.

There is shown in connection with Figs. 1 to 3 a pressure gage M_a connected with the steam accumulator by means of a pipe L_m , the operation of which gage is fully set forth in my application Serial No. 305,622; and as this pressure gage is not directly concerned with the present invention it will not be necessary for a complete understanding of the invention to describe the same more fully herein.

Having thus described my invention, what I claim is:

1. A steam plant comprising in combination a steam generator, a steam conduit connected thereto, a steam motor connected to said conduit, said motor comprising a plurality of units including a low pressure unit, regulating means to control the steam supply to the motor from said conduit, means actuated by the pressure in the conduit from which the motor is supplied, and operating to control the supply of steam to the low pressure unit and a steam accumulator connected to the motor ahead of said last means.

2. A steam plant comprising in combination a steam generator, a steam conduit connected therewith, a steam motor comprising a high pressure unit connected with the conduit, and a low pressure unit receiving steam from the high pressure unit, a steam accumulator receiving steam from the high pressure unit, means actuated by the pressure in the conduit from which the high pressure unit is supplied and operating to throttle the steam supply to the low pressure unit upon an increase of pressure in the supply conduit above a predetermined value, and means for increasing the supply of steam to the high pressure unit when the supply to the low pressure unit is throttled.

3. A steam plant comprising in combination a steam generator, a steam conduit connected thereto, a steam motor connected to said conduit, said motor comprising a plurality of units including a low pressure unit, speed regulated means adapted to control the steam supply to the motor, a valve member adapted to control the steam supply to the low pressure unit, and means for actuating said valve member to increase the steam supply to the low pressure unit upon a decrease of the pressure below a predetermined value in the said conduit from which the motor is supplied, while throttling the steam supply upon an increase of said pressure above a predetermined value, and a steam accumulator receiving steam from the motor ahead of said valve member.

4. A steam plant comprising in combination

tion a steam generator, a steam conduit connected thereto, a steam motor comprising a high pressure unit connected to said conduit and a low pressure unit, a connection receiving steam from the high pressure unit and passing steam to the low pressure unit, speed regulated means adapted to control the steam supply to the high pressure unit, a valve member adapted to control the steam supply to the low pressure unit, means for actuating said valve member to increase the steam supply to the low pressure unit upon a decrease of the pressure below a predetermined value in the said conduit from which the high pressure unit is supplied, while throttling the steam supply upon an increase of said pressure above a predetermined value, a steam accumulator, a connection between said accumulator and the connection passing steam to said low pressure unit, and a second speed regulated means arranged in the connection passing steam to said low pressure unit in back of the point where said accumulator is connected adapted to throttle the steam supply to the low pressure unit when the steam supply to the high pressure unit is cut off.

5. A steam plant comprising in combination a steam generator, a steam conduit connected thereto, a steam motor comprising a high pressure unit connected to the conduit and a low pressure unit, a conduit receiving steam from the high pressure unit and connected to the low pressure unit to supply steam thereto, regulating means to control the steam supply to the high pressure unit, controlling means actuated by the pressure in the conduit from which the high pressure is supplied and operating to control the supply of steam to the low pressure unit, and a steam accumulator communicating with the second mentioned conduit at a point in front of said controlling means.

6. A steam plant comprising in combination a steam generator, a steam conduit connected thereto, a steam motor comprising a high pressure unit connected to said conduit and a low pressure unit receiving steam from the high pressure unit, regulating means to control the steam supply to the high pressure unit, a steam accumulator receiving steam from the high pressure unit, and means actuated by the pressure in the conduit from which the high pressure unit is supplied, and operating to control the supply of steam to the low pressure unit.

7. A steam plant comprising in combination a steam generator, a steam conduit connected thereto, a steam motor comprising a high pressure unit connected to said conduit and a low pressure unit receiving steam from the high pressure unit, regulating means to control the steam supply to the high pressure unit, a steam accumulator receiving steam from the motor, means actu-

ated by the pressure in the conduit from which the high pressure unit is supplied and operating to control the supply of steam to the low pressure unit, and a steam consumer supplied with steam from the high pressure unit.

8. A steam plant comprising in combination a steam generator, a steam conduit connected thereto, a steam motor comprising a high pressure unit connected to said conduit, an intermediate pressure unit receiving steam from the high pressure unit, and a low pressure unit receiving steam from the intermediate pressure unit, regulating means to control the steam supply to the high pressure unit, means actuated by the pressure in the conduit from which the high pressure unit is supplied and operating to control the supply of steam to the low pressure unit, a conduit supplied with steam from the high pressure unit, a steam consumer connected therewith, a conduit receiving steam from the intermediate pressure unit, a steam consumer connected thereto, and a steam accumulator connected to the last mentioned conduit.

9. A steam plant comprising in combination a steam generator, a steam conduit connected thereto, a steam motor comprising a high pressure unit connected to said conduit, and a low pressure unit receiving steam from the high pressure unit, regulating means to control the steam supply to the high pressure unit, a steam accumulator receiving steam from the high pressure unit, means actuated by the pressure in the conduit from which the high pressure unit is supplied and operating to control the supply of steam to the low pressure unit, and to cut off said supply when the pressure in the steam conduit increases above a predetermined value, a branch conduit connecting the said conduit from which the motor is supplied, with the accumulator, and a valve mechanism in said branch conduit adapted to open and admit steam in direction toward the accumulator upon an increase of pressure in the first conduit above the value sufficient to shut off the steam supply to the low pressure unit.

10. A steam plant comprising in combination a steam generator, a steam conduit connected thereto, a steam motor comprising a high pressure unit connected to said conduit and a low pressure unit receiving steam from the high pressure unit, speed regulated means adapted to control the steam supply to the high pressure unit, a steam accumulator receiving steam from the high pressure unit, a valve member adapted to control the steam supply to the low pressure unit, means for actuating said valve member to increase the steam supply to the low pressure unit upon a decrease of the pressure below a predetermined value in the said conduit, while

- throttling the steam supply upon an increase of said pressure above a predetermined value, a branch conduit connecting the first mentioned conduit with the accumulator, and a valve mechanism in said branch conduit adapted to open and admit steam in direction toward the accumulator upon an increase of pressure in the first mentioned conduit sufficient to shut off the steam supply to the low pressure unit.
11. A steam plant comprising in combination a steam generator, a steam conduit connected thereto, a steam motor comprising a high pressure unit connected to said conduit and a low pressure unit receiving steam from the high pressure unit, regulating means to control the steam supply to the high pressure unit, a steam accumulator receiving steam from the high pressure unit, means actuated by the pressure in the conduit from which the high pressure unit is supplied and operating to control the supply of steam to the low pressure unit, and a steam consumer supplied with steam direct from the said conduit.

In testimony whereof I affix my signature in presence of two witnesses.

JOHANNES KARL RUTHS.
